(57) **CLAIM**

The ornamental design for a vehicle interior door handle, as shown and described.

DESCRIPTION

FIG. 1 is a perspective view of a vehicle interior door handle showing our new design;

FIG. 2 is a side elevational view thereof; and,

FIG. 3 is a top plan view thereof.

The broken lines shown represent unclaimed subject matter and form no part of the claim. Where broken lines abut a claimed surface it is understood that those broken lines represent an unclaimed boundary between claimed and unclaimed surfaces. None of the broken lines form any part of the claimed design.
